UNITED STATES PATENT OFFICE.

JOHN L. HAYTER, OF NEW BRUNSWICK, NEW JERSEY, ASSIGNOR TO GEORGE F. McCORMICK, OF NEW BRUNSWICK, NEW JERSEY.

AUTOMATIC TRAIN-CONTROL MECHANISM.

Application filed August 4, 1922. Serial No. 579,564.

To all whom it may concern:

Be it known that I, JOHN L. HAYTER, a citizen of the United States, residing in New Brunswick, in the county of Middlesex, in the State of New Jersey, have invented certain new and useful Improvements in Automatic Train-Control Mechanisms, of which the following is a specification.

10 The invention relates to an improvement in automatic train control mechanisms designed to reduce the speed of the train or to bring it to a full stop, according to road conditions as determined by the electric signal system with which the railway is equipped.

One object of the invention is to produce a train control mechanism which will control the operation of the brakes of the train 20 according to the actual road condition, whether or not the signal indicates that condition. To this end an electro-magnet is provided, adapted for location in the road bed of the railway and connected with the 25 relay switches forming a part of the electric signal system. By connecting the electro-magnet for actuating the brake operating device carried by the train with the relay switches of the signal system, the energization of the magnet is preferably controlled entirely by the road conditions existing in the block with which the magnet is connected and is not dependent upon the operation of the signal which, as is well-known, sometimes fails to operate and indicate the actual road condition.

A further object of the invention is to produce a train control mechanism which will operate, according to road conditions, to 40 reduce the speed of the train in one block, then if the road conditions, which call for the reduction of speed in the train still persist in the next succeeding block, to completely stop the train. If the road conditions in the next succeeding block require caution in the block which the train is entering (this situation being indicated by the signal assuming a 45° position) the train control mechanism of the present invention 50 operates to cause a service application of the brakes to thereby gradually reduce the speed of the train as it proceeds through the block. There is a service application of the brakes under caution conditions at whatever speed the train enters the caution block,

whether at high speed or whether at a speed below that to which a service application of the brakes usually reduces the train. The object of this mode of operation is to insure such a reduction in the speed of the train 60 that if the road conditions in the next block necessitate stopping the train by an emergency application of the brakes, the speed of the train will have been so far reduced that the emergency application of the brakes 65 will cause a substantially instantaneous stopping of the train.

Another and more general object of the invention is to simplify and improve upon the construction of automatic train control 70 mechanisms in order to reduce the weight and cost of manufacture of such mechanisms and to produce one which is adapted for application to existing equipments without material or expensive changes or alterations therein. These and other objects of the invention, which will appear as the description thereof proceeds, are accomplished in the improved automatic train control mechanism hereinafter described and particularly pointed out in the appended 75 claims.

The improved train control mechanism is adapted for application to and use in conjunction with the more usual types of block 80 signal systems. Two of these systems are in common and well-known use. In the first, the three position signal is controlled from a single relay box which contains all the contact points and switches for controlling the passage of the current from the battery to the solenoids actuating the signal. This relay box is known technically as a three position relay. In addition to the various contact points, the relay contains a 85 polarized magnet connected with the switches and energized by the battery of a pole changer located in the next succeeding block. Thus the polarity of the polarized magnet is changed by the pole changer according to track conditions in the next succeeding block. The track conditions are indicated by the signal connected with that block, and the signal is mechanically connected with the pole changer. In the second common type of block signal system, each block is provided with two separate relays corresponding to the 90° or clear track position of the signal and to the 45° or caution position of the signal. The opera- 100 105 110

tion of the devices in these individual relays is partly controlled by the next succeeding block, but the control is entirely according to the actual track conditions existing in the 5 block and not through a mechanical connection with the signal.

Thus when the train control mechanism of the present invention is applied to a railroad or railway equipped with a signal system which uses two separate relays for each 10 block and the signal operating devices are controlled entirely by road conditions and not by the signal of the next block, the train control mechanism operates to control the 15 application of the brakes entirely according to road conditions and irrespective of the positions of the signals. If the train control mechanism is applied to a signal system employing a single three position relay 20 in which the polarized magnet is connected with a pole changer operated mechanically by a signal, then the train control mechanism operates partly in response to actual road conditions and partly in response to 25 road conditions as indicated by the signal.

The preferred form of the invention is illustrated in the accompanying drawings in which Fig. 1 is a section through the valve for controlling the train brake pipe 30 and through the means for actuating the valve. The means for determining the operation of the valve is illustrated diagrammatically. Fig. 2 is a longitudinal section showing the position of the parts when the 35 train brake pipe is connected with the emergency vent. Fig. 2 also shows the relation between the valve of the present invention and a standard engineer's brake valve. Fig. 3 is a diagrammatic view showing the position 40 of the armature and associated parts when an emergency condition exists in the track. Fig. 4 is a view similar to Fig. 2 showing the position of the parts when the valve connects the train brake pipe with 45 the service vent. Fig. 5 is a diagrammatic view similar to Fig. 3, showing the position of the armature and associated parts when a caution condition exists on the track. Fig. 6 is an enlarged sectional detail through 50 one of the solenoid operated valves for admitting compressed air to one of the valve actuating pistons. Fig. 7 is a top plan of the engineer's brake valve showing its relation to certain parts of the present mechanism. And Fig. 8 is a diagram of a block 55 signal system employing a non-polarized circuit, and showing the connections between the system and the track magnet of the present train control mechanism.

60 The improved train control mechanism of the present invention, as illustrated in the drawings, comprises a track magnet located in the road bed of the railway. The track magnet may be placed at any preferred distance in advance of the block with which

it is connected and whose track conditions are to control the oncoming train through the magnet. The track magnet is directly connected with the block signal system with which the railway is equipped. The block 70 signal system is made use of to control the direction of current flow through the track magnet. If the current operating the switches in the relay box is shunted or short circuited from the relay, thereby indicating 75 that a train is in the block, a switch open, a rail broken, or that some similar condition prevails, the current from the relay battery will flow through the track magnet in one direction to bring about an emergency application of the brakes on the oncoming train. If the preceding train has just left the block, so that the relay is again placed in circuit, this situation being known as a caution condition of the block, the current 80 flows through the track magnet in the opposite direction, thereby effecting a service application of the brakes on the oncoming train. If the track conditions prevailing in the block require an emergency application of the brakes, this will be automatically effected under all conditions by the train control mechanism of the present invention, whether or not the signal indicates that condition. That is to say, the emergency application of the brakes is governed entirely by the track conditions and not by the position of the signal.

Whether the service application of the brakes will be controlled directly by the 100 track conditions or will be controlled by the track conditions as indicated by the position of the signal will depend upon the type of block signal system with which the railway is equipped. When a signal system having 105 a three position relay is used and the system includes a pole changer for changing the polarity of the contact points in the relay box, the usual construction is to have the operation of the caution signal of the first block 110 (under consideration) depend upon the mechanical operation of the next succeeding signal. Under these conditions the automatic service application of the brakes will depend upon the operation of the next succeeding signal. But where a signal system is used which is not provided with either polarized contact points or a pole changer, then the service application of the brakes 115 will be controlled directly by track conditions. The automatic train control mechanism of the present invention will be described in connection with these two standard types of block signal systems.

The polarized track magnet is adapted to 125 actuate a constant pole armature carried by the train. The armature controls the operation of a three position valve which is connected with the train brake pipe. If the armature is moved in one direction by the 130

track magnet, the valve is moved to connect the brake pipe with a service vent and so bring about a service application of the brakes. If the armature is moved in the opposite direction by reason of the track magnet having an opposite polarity, the valve is moved to connect the brake pipe with an emergency vent and so bring about an emergency application of the brakes. Thus the application of the brakes, whether service or emergency, is controlled by the polarity of the track magnet, which in turn is controlled by the track conditions in the block with which the magnet is connected.

15. In the illustrated embodiment of the invention, the three position valve for controlling the brakes is indicated generally at 19. The valve comprises a cylindrical casing 11 which houses the valve proper 12 formed as a double ended piston and having a recessed middle portion 13. The valve casing 11 is provided with a central opening adapted to be connected with the train brake pipe 14. The three position valve is operated independently of the engineer's valve indicated at 15; and the engineer's valve in turn may be operated independently of the three position valve, as indicated in the drawings. However, if the track conditions automatically effect an operation of the three position valve either to cause a service or an emergency application of the brakes and the engineer turns the handle 16 of his valve to either service or emergency position, then the three position valve will be restored to normal position, as shown in Fig. 1. This mode of operation will appear more fully hereinafter. The handle 16 of the engineer's valve is shown in Fig. 7 in the position it occupies when the train is running.

The valve casing 11 is also provided with a service vent 17 and an emergency vent 18. When the track conditions require a service application of the brakes, the valve 12 will be moved to the right, as shown in Fig. 4, thereby connecting the brake pipe with the service vent and so bring about a service application of the brakes. If, however, the track conditions require an emergency application of the brakes, the valve 12 will be moved to the left, as shown in Fig. 2, and thereby bring about an emergency application of the brakes.

55. The illustrated means for actuating the three position valve 12 comprises two pistons 20 and 21 located respectively in the cylinders 22 and 23 which are secured at their inner ends 24 to the flanged outer ends 25 of the valve casing 11. The pistons 20 and 21 are mounted on the outer ends of the piston rods 26 screwed into the ends of the valve 12. Two compression springs 27 and 28 interposed between the ends of the 60 valve and diaphragms 29 serve to hold the

valve in normal position, as indicated in Fig. 1.

The pistons 20 and 21 which actuate the valve 12 are moved by means of compressed air. The compressed air is admitted to the piston 20 through a solenoid controlled valve 30 connected at its lower end 31 with a source of compressed air, preferably the main reservoir on the engine. The solenoid 32 is wound in the usual manner and is 70 adapted to actuate, when energized, an armature 33. The armature 33 is provided with a downwardly extending rod 34, the lower end of which carries the stem 35 of a valve 36 normally pressed upwardly 80 against its seat by a spring 37. When the track conditions require a service application of the brakes, the solenoid 32 is energized to draw the armature 33 downwardly and thereby unseat the valve 36. The compressed air then passes through the spider 38, up through the valve opening and into the cylinder 22, pushing the piston 20 and the valve 12 to the right to connect the 85 brake pipe with the service vent. The downward movement of the armature rod 34 causes the valve 40 formed on the lower end of the rod to close the vent 41. The valve 12 remains in its moved position (as will hereinafter appear) until the engineer 90 breaks the circuit connected with the solenoid 32 by shifting the handle 16 of the engineer's brake valve 15 to service position indicated by the dot and dash line 42 in Fig. 7, or (if the service application of the brakes should stop the train) until the engineer turns the handle 16 to release position indicated by the dot and dash line 39. An automatic emergency application of the brakes 95 also breaks the circuit of the solenoid 32, as 100 will presently appear. When the solenoid 32 is deenergized, the spring 37 lifts the armature rod 34, closing the valve 36 and opening the relief valve 40, thereby permitting the air to escape out through the 105 vent 41. The spring 28 then restores the valve 12 to its normal position.

When the track conditions require an emergency application of the brakes, compressed air is admitted to the piston 21 through a solenoid controlled valve 43 to move the valve 12 to the left and thereby connect the brake pipe with the emergency vent 18. The valve 43 and its solenoid 44 are constructed and operate exactly like the 115 valve 30 and its solenoid 32, and therefore do not require a detailed description. The corresponding parts of both valves are indicated by the same reference numerals in the enlarged detail in Fig. 6.

The solenoids 32 and 44 are located in normally open circuits. When these circuits are closed the solenoids derive their energy from the battery 45. The solenoid circuits are adapted to be closed when the permanent 120

magnet 47, which serves as an armature, is actuated by the track magnet 48. The armature 47 and its connected mechanism are enclosed in a housing, which for clearness of illustration is not shown. This housing is so located on the engine that the lateral extensions 49 and 50 of the lower end of the armature pass in close proximity to the upper ends of the poles 51 and 52 of the track magnet 48. The armature is pivotally mounted at 54, so that its upper end 56, which serves as a circuit closer, may swing into contact with either the contact points 57 or the contact points 58. The lower end 15 of the armature having a permanent polarity and the polarity of the poles 51 and 52 of the track magnet 48 changing according to track conditions, it will be seen that the armature will be swung in different directions according to the polarity of the track magnet.

It is assumed that the lower end of the armature 47 is a constant north pole, and that when emergency conditions obtain in 25 the block the current directed through the track magnet will cause the pole 51 to be north and the pole 52 to be south. The armature will then swing in a clockwise direction (as shown in Fig. 3), thereby bringing the contact head 56 across the contact springs 58 and closing the circuit in which the solenoid 44 is located. The circuit may be traced as follows: Starting from the point 61 at the solenoid 44, the current passes through the wire 62 into the contact arc 63 and thence through the handle 16 of the engineer's valve 15 into the negative side of the battery 45. From the positive side of the battery the current passes 30 through the wires 65, 66, 67 and 68 to the stick magnet 69. From the stick magnet 69 the current passes through the wire 71, through the contact points 58 and through the wires 72 and 73 to the solenoid 44. 45 When the engineer has turned the handle of the brake valve 15 to emergency position as shown by the dot and dash line 64 in Fig. 7, the contact point 74 (Figs. 2 and 7) passes beyond the end of the contact arc 63, thereby breaking the circuit in which the solenoid 44 is located and permitting the three position valve 12 to return to normal position. The turning of handle 16 of the engineer's valve to release position when the 50 train has been stopped by an automatic emergency application of the brakes also restores the valve parts to normal position by breaking the circuit of solenoid 44.

When service conditions obtain in the 55 block and the current is directed through the track magnet in the opposite direction so as to reverse the polarity of the poles 51 and 52, making the pole 52 north and the pole 51 south, the armature 47 is actuated to swing in a counter-clockwise direc-

tion, (as shown in Fig. 5) thereby bridging the contact springs 57 through the contact head 56. The bridging of the contact springs 57 places the solenoid 32 in circuit with the battery 45. This circuit is traced 70 as follows:—Starting at the solenoid 32 the current passes through the wire 76 to the contact arc 77, and thence through the handle of the engineer's valve to the negative side of the battery. From the positive side 75 of the battery the current passes the wires 65, 66, 67 and 78 to the stick magnet 79. From the magnet 79, the current passes through the wire 80 to the bridged contact points 57 and thence through the wires 82 80 and 83 to the solenoid 32. When the engineer turns the handle of the brake valve to service position in response to caution conditions on the track, the contact point 85 passes beyond the end of the contact arc 85 77, thereby breaking the circuit in which the solenoid 32 is located, and permitting the valve 12 to return to normal position. Also when the engineer turns the handle of his 90 brake valve to release position the circuit through the solenoid 32 will be broken, and the valve 12 will be turned to normal position.

The means for holding the armature in its moved position to keep the circuits of the 95 solenoids 32 and 44 closed comprises a pair of magnets 69 and 79 which are known in the art as "stick" magnets. When the armature 47 has been swung in a clockwise direction, closing the circuit through the solenoid 100 44 and incidentally energizing the magnet 69, an armature piece 87 carried by an insulating block 88 mounted on the armature 47 is attracted to and held by the magnet 69, thereby keeping the contact springs 58 105 bridged until the engineer breaks the circuit by moving the handle of his brake valve to emergency position or to release position. In like manner, when the armature 47 has been swung in counter-clockwise direction, 110 thereby bridging the contact springs 57 and closing the circuit through the battery 45 and the solenoid 32, the magnet 79 is incidentally energized, and the armature piece 89 carried on the other end of the block 88 is attracted to and held fast by the magnet 79. Thus the contact springs 57 are kept bridged and the solenoid 32 energized until the circuit is broken by the engineer. If there has been an automatic service application 115 of the brakes and the engineer does not turn his valve handle to service or release position, and the train approaches the emergency block, the track magnet 48 being stronger than the stick magnet 79, the attraction between magnet 79 and armature 89 will be overcome when the track magnet actuates the armature 47 to expect an emergency application of the brakes. The breaking of either circuit permits the balance 120 125 130

springs 90 and 91, connected with the upper end of the armature 47, to return and hold it in normal position. To increase the magnetic flux through the pole pieces 49 and 50 carried by the lower end of the armature 47, an electro-magnet 93 in constant circuit with the battery 45 is provided. This circuit is traced from the positive side of the battery through the wires 65, 66, 67, 78 and 94 to the magnet 93. From the magnet the current passes through the wires 95, 96, 97 and 98 to the negative side of the battery.

The connections between the track magnet 48 and a block signal system having 15 polarized contact points will be described first and then the connections between the track magnet and a block signal system having non-polarized circuits will be described. The block signal system having 20 polarized contact points is illustrated diagrammatically, in the usual manner, in the lower left hand corner of Fig. 1. The railway tracks are indicated at 100 and 101. The pole changer is shown at 102. Normally the current passes from the positive side of the battery 103 through the switch 104 and wire 105 to track 101, and from there through the wire 106 to the relay box 107, and from the relay box through wire 108, the track 100 and switch 109 to the negative side of the battery 103. When the relay 107 is receiving current from battery 103, while the contact switches 104 and 109 are in the positions indicated in full lines 35 in Fig. 1 (this being their normal position, with the track in block Y clear), the switches 110 and 111 are picked up against the contact points 112 and 113, and the switches 120 and 121 are in engagement with the contact points 122 and 123. The switches 104 and 109 of pole changer 102 are mechanically connected with the signal 99 of block Y. When signal 99 is in clear or caution position (the track of block Y being clear) 40 the switches 104 and 109 are held in normal position by the signal.

The points 112 and 113 are in circuit with the solenoid which controls the caution position of the signal 128, and the points 122 and 123 are in circuit with the solenoid which controls the clear position of said signal. The caution position solenoid circuit is made from the battery 114 through the switch 110 and the point 112 to the solenoid. From the solenoid the current returns through the point 113, the switch 111 and the wire 115 to the battery 114. The clear position solenoid circuit is made from the positive side of the battery through the switches 110 and 121 to the contact point 122 and thence to the solenoid. From the solenoid the current returns through the point 123, the switches 120 and 111, and the wire 115 to the battery. Thus when the pole changer is in normal position, the signal 128 is held in its 90° or clear position. When, however, the switches 104 and 109 have been swung into contact with the points 117 and 118, owing to the fact that a train has passed into block Y and the signal 99 has dropped to zero or stop position, the polarity of the contact points in the relay box 107 is changed, as will be seen by tracing the circuit from the positive side of the battery 103.

Before the train entered block Y it passed through block X, and that caused relay 107 to be shunted from battery 103. Thereupon the switches 110 and 111 broke contact with the points 112 and 113 and signal 128 fell to zero or stop position, as shown. When the train passed out of block X and into block Y thereby putting relay 107 into circuit with the pole changer 102 again, the switches 110 and 111 were brought into contact with the points 112 and 113 and the signal 128 was raised to 45° or caution position. When the polarity of the relay 107 was thus changed the switches 120 and 121 broke contact with the points 122 and 123. When the train leaves block Y, switches 104 and 109 return to normal position (with the return of signal 99 to its 90° or clear position) and the polarity of relay 107 is restored to normal with the result that switches 120 and 121 again contact with points 122 and 123 and the signal 128 is raised to its 90° or clear position.

Assuming now that a train, indicated by the truck 125, has entered block X, the current from battery 103 is shunted by the truck and the relay 107 cut off. The switches 110 and 111 drop out of connection with the points 112 and 113 and into contact with the points 126 and 127. When this occurs the current ceases to flow through the switches 120 and 121, although they still remain in contact with the points 122 and 123, and the signal 128 drops to its zero or stop position. This situation requires an emergency application of the brakes. Accordingly, current is caused to flow from the battery 114 through the track magnet 48 in a direction to bring about a connection between the train brake pipe and the emergency vent in the manner described above. This current passes from the battery 114 through the switch 110, the point 126 and the wire 129 to the pole 51 making it a north pole; and from the latter through the connecting wire 130 to the pole 52, making it a south pole. From the pole 52 the current returns through the wire 131 to the point 127, the switch 111 and the wire 115 to the negative side of the battery.

When the train has left block X, thereby placing the relay 107 in circuit again with battery 103, the switches 110 and 111 are again picked up against the points 112 and 113, and the signal 128 is raised to its 45°

or caution position. This condition in the relay box 107 causes the switches 120 and 121 to be disconnected from the points 122 and 123 and to come into contact with the points 133 and 134, thereby causing the current to flow through the track magnet 48 in the opposite direction, making the pole 52 north and the pole 51 south, to bring about a service application of the brakes. 5

10 The current from battery 114 now passes through the switches 110 and 121, the contact point 133 and the wire 131 to the pole 52, and through the wire 130 to the pole 51. From the pole 51 the current returns 15 through the wire 129, the point 134, the switches 120 and 111 and the wire 115 to the negative side of the battery. 10

15 The use of the track magnet of the automatic train control mechanism of the present invention in connection with a block signal system of the non-polarized circuit type is illustrated diagrammatically in Fig. 8. The drawing is a conventional representation of a standard form of signal mechanism. The track magnet 48 is shown connected with the signal circuit in such manner that the pole 51 will be north during an emergency condition in the block with which the magnet is connected, and 20 the pole 52 will be north during a caution condition in the block. When the track is clear, the track magnet will be cut off from the signal battery. It is assumed that a train, represented by the truck 140, has 25 passed through blocks A and B and has entered block C. This causes the current from the battery 141 to be short circuit from the relay box 142. Thereupon the switches 143 and 144 will fall away from the contact points 145 and 146, respectively, the switches 147 and 148 will fall away from the contact points 149 and 150, respectively, and the switches 151, 152 and 153 will fall away from the contact points 154, 155 and 156, as will be understood by those skilled 30 in the art, and signal 158 will fall to zero or stop position. The switches 143 and 144 fall upon the dead contact points 159 and 160, and the switches 151 and 152 fall 35 upon the contact points 162 and 163, which are connected respectively with the wires 164 and 165, thereby establishing a circuit from the battery 166 to the track magnet 48. The circuit is traced from the positive 40 side of the battery through the wire 168, the switch 152, contact point 163 and the wire 165 to the pole 51, making the latter north. From the pole 51 a current passes 45 through the wire 169 into the pole 52 making the latter south, and from the pole 52 the current returns through the wire 164, the contact point 162, switch 151 and the wire 170 to the negative side of the battery. Thus the track magnet 48 is energized to 50 bring about an emergency application of the

brakes in case the next train should attempt to enter block C.

When the train left block B and entered block C, the battery 172 became connected again with the relay box 173. Inasmuch as 70 the contacts and wires in relay box 173 are the exact duplicate of those in relay box 142, the same reference numerals will be used to indicate them. When the current from battery 172 again passes through relay box 173, 75 the switches 143 and 144 are picked up against the points 145 and 146, the switches 147 and 148 are picked up against the points 149 and 150 and the switches 151, 152 and 153 are picked up against the points 154, 155 and 156, with the result that the signal 80 175 is raised from stop position to caution position as indicated. Under these conditions, the current from battery 176 flows through the track magnet 48 in the reverse 85 direction, making the pole 52 north and the pole 51 south, to bring about a service application of the brakes in case a train should enter block B. The circuit is traced from the positive side of the battery through the wire 177, the switch 147 and contact 149 to the switch 178. From switch 178 the current passes through the wire 179 to the pole 52 and from pole 52 to the pole 51. From the pole 51 the current returns through 90 the wire 180 to the switch 181, and from the switch 181 through the wire 182 to the contact point 150 and switch 148 to the negative side of the battery. 95

While the signal 175 of block B is in 100 caution position, signal 184 of block A will be in its 90° or clear track position. The clear track position of the signals is controlled by the caution position of the next succeeding signal, and the signal is lifted into 105 clear position by the battery of the next succeeding relay box. Thus when the signal 175 of block B is in caution position, the circuit from battery 176 to the solenoid 185, which controls the position of signal 184, 110 is traced through wire 168, switch 152 contact point 155 and wire 186 to contact 156 and switch 153 (of block A) and through wire 188 to the solenoid 185. From the solenoid the current returns through wire 115 189 to contact 154 and switch 151 (of block B) and through wire 170 to the negative side of the battery. It will have been observed that the lifting of switches 151 and 152 (of block B) against contact points 154 and 120 155 broke the emergency connection between battery 176 and the track magnet. In like manner, it will be observed that the energization of the solenoid 185 lifts the switches 178 and 181 and thereby severs the track magnet 125 from battery 190.

Briefly, the operation of the improved automatic train control mechanism is as follows:—When the track conditions in a block require an emergency application of the 130

brakes, current from the battery of the block signal system passes through the track magnet 48 in a direction to make the pole 51 north and the pole 52 south. This causes 5 the pole 51 to repel the arm 49 of the armature 47, and the pole 52 to attract the arm 50, thereby swinging the arm 47 in a clockwise direction and closing the circuit through the solenoid 44 by bridging the 10 contact springs 58 by means of the contact head 56. At the same time the magnet 69 is energized to attract the armature piece 87 and hold the contact head 56 in engagement with the contact springs 58. The 15 energization of the solenoid 44 opens the valve 43 in the manner described and permits air under compression to enter the cylinder 23 and force the piston 21 and valve 12 to the left, as shown in Fig. 2. 20 Thus the train brake pipe 14 is connected with the emergency vent 18, and the result is an emergency application of the brakes. This position of the parts of the train control mechanism continues until the engineer 25 turns the handle of the brake valve 15 to emergency position or to release position, thereby disengaging the contact 74 from the contact arc 63 and breaking the circuit through solenoid 44, which permits the parts 30 to return to normal position.

When the track conditions of the block require a service application of the brakes on the oncoming train, current from the block signal system flows through the track magnet in the opposite direction, making the pole 52 north and the pole 51 south. The arm 50 is now repelled by the pole 52, and the arm 49 is attracted by the pole 51. This action swings the armature 47 in a 40 counter-clockwise direction, so that the contact head 56 bridges the contact springs 57 and energizes solenoid 32. At the same time, the stick magnet 79 is energized to attract the armature piece 89 and hold the contact 45 head 56 in engagement with the contact springs 57. The energization of the solenoid 32 actuates the valve 30 to permit compressed air to force the piston 20 and valve 12 to the right to connect the brake pipe 50 with the service vent, as shown in Fig. 4. The parts normally remain in these positions until the engineer turns the handle of his brake valve to service or release position, and thereby disconnects the contact 85 from the 55 arc 77, breaking the circuit through solenoid 32 and permitting the parts to return to normal position. If the train is proceeding at such rate of speed that the automatic service application of the brakes completely stops the train, the turning of the 60 handle of the engineer's valve to release position breaks the circuit through solenoid 32 and the parts of the train control mechanism are restored to normal position.

65 In the foregoing description of the mode

of operation of the improved train control mechanism the automatic emergency application of the brakes has for convenience been described first. It will be understood, however, that in actual practice an automatic service application of the brakes will almost always precede an automatic emergency application of the brakes. This is because, under usual conditions, a caution condition exists in the block preceding the 70 block in which the danger conditions exist. When a train is in a block, that constitutes a danger condition in that block. When the train leaves that block and enters the next succeeding block, the latter becomes the danger block and the former becomes the caution block. Under these circumstances, there would, of course, be first a service application of the brakes if an oncoming train attempted to enter the caution block and then an emergency application of the brakes if the train attempted to enter the danger block. 75 80 85

Having thus described the invention what I claim as new is:—

1. An automatic train control mechanism 90 having, in combination, a magnet located in the road bed of the railway and connected with the block signal system, the connections between the magnet and the signal system being such that an emergency condition of the track causes current to flow through the magnet in one direction and a caution condition of the track causes the current to flow through the magnet in the opposite direction, a permanent pole armature 95 carried by the train to pass in close proximity to the magnet, a valve connected with the train brake pipe and having a service vent and an emergency vent, and means for actuating the valve, said means being controlled by the armature to connect the brake pipe with either the service vent or the emergency vent according to the polarity of the track magnet. 100 105

2. An automatic train control mechanism 110 having, in combination, a track magnet connected with the block signal system, an emergency condition of the track causing the current to flow in one direction through the magnet and a caution condition of the 115 track causing the current to flow through the magnet in the opposite direction, a permanent pole armature carried by the train to pass in close proximity to the track magnet, a valve adapted to be actuated to connect the train brake pipe with a service vent and with an emergency vent, means for actuating the valve, and means connected with the armature for controlling the valve actuating means according to the polarity of 120 125 the track magnet.

3. An automatic train control mechanism having, in combination, a track magnet the direction of current flow through which is controlled by a block signal system accord- 130

ing to track conditions, a permanent pole armature carried by the train to pass in close proximity to the track magnet to be actuated thereby, a valve for connecting the 5 train brake pipe with a service vent or with an emergency vent according to the polarity of the track magnet, resilient means for holding the valve in normal position, means for actuating the valve, and means connected with the armature for controlling the valve actuating means.

4. An automatic train control mechanism having, in combination, a track magnet connected with the block signal system, an 15 emergency condition of the track causing the current to flow through the magnet in one direction and a caution condition of the track causing the current to flow in the opposite direction, an armature carried by the 20 train to pass in close proximity to the track magnet to be moved thereby in one of two directions according to the polarity of the magnet, a valve adapted to connect the train brake pipe with an emergency vent or with 25 a service vent according to the direction in which the armature is moved, compressed air operated means for actuating the valve, and means connected with the armature for controlling the passage of compressed air 30 to the valve actuating means.

5. An automatic train control mechanism having, in combination, a track magnet connected with the block signal system, the current flowing through the magnet in different 35 directions according as emergency or caution conditions prevail in the block, a valve adapted to be actuated to connect the train brake pipe with a service vent or with an emergency vent according to the polarity 40 of the track magnet, and means carried by the train and adapted to be actuated by the track magnet for controlling the actuation of the valve.

6. An automatic train control mechanism 45 having, in combination, a valve adapted to be actuated to connect the train brake pipe with an emergency vent and with a service vent, means for actuating the valve, an armature carried by the train for controlling 50 the valve actuating means, a magnet located in the road bed of the railway adapted to actuate the armature, and connections between the magnet and the block signal system to cause current to flow through the 55 magnet in one direction for an emergency condition of the track and to cause the current to flow through the magnet in the opposite direction for a caution condition of the track.

60 7. An automatic train control mechanism having, in combination, a magnet located in the road bed of the railway, connections between the magnet and the block signal system whereby the current flows through 65 the magnet in different directions according

as an emergency or a caution condition prevails in the block, an armature carried by the train to pass in close proximity to the track magnet and adapted to be moved thereby in one of two directions according 70 to the polarity of the magnet, a valve connected with the train brake pipe and having a service vent and an emergency vent, and means controlled by the armature for operating the valve to connect the brake pipe 75 with either vent.

8. An automatic train control mechanism having, in combination, a two pole track magnet connected with the block signal system, an emergency condition in the block 80 causing the current to flow through the magnet in one direction and a caution condition in the block causing the current to flow through the magnet in the opposite direction, an armature carried by the train to 85 pass in close proximity to the track magnet, said armature having lateral arms of fixed polarity so that the armature is moved in different directions according to the polarity of the track magnet, two solenoids in normally open circuits adapted to be closed by the armature, a valve adapted to be actuated to connect the train brake pipe with an emergency vent or with a service vent according to the polarity of the track magnet, 90 compressed air operated means for actuating the valve, and means controlled by the solenoids for regulating the passage of air 95 to the valve actuating means.

9. An automatic train control mechanism having, in combination, a track magnet connection with a block signal system whereby an emergency condition of the block causes current to flow through the magnet in one direction and a caution condition of the block causes current to flow through the magnet in the opposite direction, a valve adapted to be actuated to connect the train brake pipe with a service vent or with an emergency vent according to the polarity 100 of the track magnet, compressed air operated means for actuating the valve, two solenoids for controlling the passage of compressed air to the valve actuating means, 110 said solenoids being located in normally open circuits, a permanent pole armature carried by the train to pass in close proximity to the track magnet, said armature being moved in one of two directions according to the polarity of the track magnet 115 to thereby close one or the other of the circuits in which the solenoids are located.

10. An automatic train control mechanism having, in combination, a two pole track magnet connected with a block signal system, an emergency condition of the block causing current to flow through the track magnet in one direction and a caution condition of the block causing current to flow through the track magnet in the opposite 120 125 130

direction, a valve adapted to be actuated to connect the train brake pipe with an emergency vent or with a service vent according to the polarity of the brake magnet, balanced springs for holding the valve in normal position, means for actuating the valve, and a permanent pole armature carried by the train to pass in close proximity to the track magnet and adapted to be moved in one of two directions according to the polarity of the track magnet, said armature serving to control by its position the operation of the valve actuating means.

11. An automatic train control mechanism having, in combination, a two pole track magnet connected with a block signal system, the current flowing through the track magnet in one of two directions according as an emergency or a caution condition prevails in the block, a valve adapted to be actuated to connect the train brake pipe with an emergency or with a service vent according to the polarity of the track magnet, means tending to hold the valve in normal position, means for actuating the valve to connect the brake pipe with either the emergency vent or the service vent, a permanent pole armature carried by the train to pass in close proximity to the track magnet to be moved thereby in one of two directions according to the polarity of the magnet and connections between the valve actuating means and the armature.

12. An automatic train control mechanism having, in combination, a two pole track magnet connected with a block signal system so that an emergency condition causes the current to flow through the battery in one direction and a caution condition causes the current to flow through the magnet in the opposite direction, a valve adapted to be actuated to connect the train brake pipe with an emergency vent or with a service vent according to the polarity of the track magnet, means for actuating the valve, a pair of solenoids for controlling the operation of the valve actuating means, normally open circuits in which the solenoids are located, a permanent pole armature carried by the train to pass in close proximity to the track magnet and adapted to be moved in one of two directions according to the polarity of the track magnet, said armature serving to close either of the two circuits according to the direction in which it is moved and a stick magnet energized by the closing of the circuit to hold the armature in its moved position.

13. An automatic train control mechanism having, in combination, a track magnet connection with a block signal system, the polarity of the magnet varying according as emergency or caution conditions exist in the block, a permanent pole armature carried by the train to pass in close proximity to the magnet to be moved thereby in one of two directions according to the polarity of the magnet, a valve adapted to be actuated to connect the train brake pipe with an emergency vent or a service vent according as the armature is moved in one or the other direction, balanced springs for holding the valve in normal position to seal the brake pipe from the vents, means for actuating the valve, and connections between the valve actuating means and the armature.

14. An automatic train control mechanism having, in combination, a track magnet connected with a block signal system, the polarity of the track magnet varying according as an emergency or a caution condition exists in the block, a valve casing connected with the train brake pipe and having an emergency vent and a service vent, a valve for connecting the brake pipe with the emergency vent and with the service vent, two solenoids, normally open circuits in which the solenoids are located and means actuated when either circuit is closed for moving the valve to connect the brake pipe with either the emergency vent or the service vent, an armature carried by the train to pass in close proximity to the track magnet to be actuated thereby to close one or the other of the circuits, and a stick magnet energized by the closing of the circuit for holding the armature in its moved position to keep the circuit closed until it is manually broken.

15. An automatic train control mechanism having, in combination, a track magnet connected with a block signal system and adapted to be energized when an emergency or a caution condition exists in the block, a valve casing connected with the train brake pipe and having a vent, a valve for sealing the brake pipe from the vent and adapted to be actuated to connect the brake pipe with the vent when the track magnet is energized, a piston connected with the valve, a solenoid for controlling the passage of compressed air to the piston, a normally open circuit in which the solenoid is located, and an armature carried by the train to pass in close proximity to the track magnet to be actuated thereby to close the circuit.

16. An automatic train control mechanism having, in combination, a track magnet connected with a block signal system and arranged to have a different polarity according as emergency or caution conditions exist in the block, a valve casing connected with the train brake pipe and having an emergency vent and a service vent, a valve for normally sealing the brake pipe from the vents, balanced springs for holding the valve in normal position, two pistons connected with the valve, two solenoids for controlling the passage of compressed air to the pistons, normally open circuits in which the sole-

- noids are located, and an armature carried by the train to pass in close proximity to the track magnet to be actuated thereby in one of two directions according to the polarity 5 of the magnet to close either circuit.
17. An automatic train control mechanism having, in combination, a track magnet connected with the block signal system and adapted to be energized when emergency and 10 caution conditions exist in the block, a valve adapted to be actuated to connect the train brake pipe with an emergency vent or with a service vent, means for actuating the valve, an armature carried by the train to pass in 15 close proximity to the track magnet to be actuated thereby, a solenoid for controlling the operation of the valve actuating means, a normally open circuit in which the solenoid is located, an armature serving to close 20 the circuit, and a stick magnet energized when the circuit is closed for holding the armature in moved position to keep the circuit closed until it is manually broken.
18. An automatic train control mechanism 25 having, in combination, a track magnet connected with a block signal system and arranged to have a different polarity according as an emergency or a caution condition exists in the block, a valve casing connected 30 with the train brake pipe and having an emergency vent and a service vent, a valve for normally sealing the brake pipe from the vents, means for actuating the valve to connect the brake pipe with the emergency vent 35 when an emergency condition exists on the track and for actuating the valve to connect the brake pipe with the service vent when a caution condition exists on the track, and means carried by the train and adapted to 40 be actuated by the track magnet for controlling the operation of the valve actuating means.
19. An automatic train control mechanism having, in combination, a track magnet connected with a block signal system, the polarity 45 of the magnet varying according as emergency or caution conditions exist in the block, a valve adapted to be actuated to connect the train brake pipe with an emergency 50 vent or with a service vent according to the polarity of the track magnet, means for actuating the valve, two solenoid-actuated means for controlling the operation of the valve actuating means, two normally open 55 circuits in which the solenoids are located, a permanent pole armature carried by the train to pass in close proximity to the track magnet to be moved thereby in one of two directions to close either circuit, and a pair 60 of stick magnets located in the circuits, the stick magnet energized by the closing of the circuit serving to hold the armature in moved position to keep the circuit closed.
20. An automatic train control mechanism 65 having, in combination, a two pole track magnet located in the road bed of the railway and connected with a block signal system, an emergency condition of the block causing the current to pass through the magnet in one direction and a caution condition 70 causing the current to pass through the magnet in the opposite direction, a valve casing connected with the brake pipe and having an emergency vent and a service vent, a valve for normally sealing the brake pipe 75 from the vents, two balanced springs for holding the valve in normal position, two pistons connected with the valve, two solenoid-actuated means for controlling the passage of compressed air to the pistons to 80 actuate the valve, two normally open circuits in which the solenoids are located, a pivoted armature carried by the train in position to pass in close proximity to the track magnet, said armature having laterally extending arms corresponding to the two poles of the track magnet, said arms having a permanent pole, the energization of the magnet causing the armature to be moved in one of two directions according to its 85 polarity to close either circuit, and a pair of stick magnets, the stick magnet energized by the closing of the circuit serving to hold the armature in moved position to keep the circuit closed until it is manually broken. 90
21. An automatic train control mechanism having, in combination, a valve adapted to be actuated to connect the train brake pipe with an emergency vent and with a service vent, means for actuating the valve, an 100 armature carried by the train for controlling the valve actuating means, means located in the road bed of the railway adapted to control the actuation of the armature, and connections between the armature controlling means and the block signal system whereby the armature is caused to move in one direction for an emergency condition of the track and to move in the opposite direction for a caution condition of the track. 110
22. An automatic train control mechanism having, in combination, a valve adapted to be actuated to connect the train brake pipe with an emergency vent when an emergency condition exists on the track and with a 115 service vent when a caution condition exists on the track, two solenoids for controlling the operation of the valve, said solenoids being located in normally open circuits, means carried by the train for closing either circuit according to track conditions, and means located in the road bed for controlling the circuit closing means connected with the block signal system to effect the closing of one circuit when an emergency condition exists on the track and to effect the closing of the other circuit when a caution condition exists on the track. 120
23. An automatic train control mechanism having, in combination, a valve adapted to 130

be moved in one direction to connect the train brake pipe with an emergency vent and in the opposite direction to connect the train brake pipe with a service vent, means for actuating the valve, two solenoids for controlling the operation of the valve actuating means, each solenoid being located in a normally open circuit, circuit closing means carried by the train for closing either circuit

according as emergency or caution conditions exist on the track, and means located in the road bed of the railway connected with the block signal system for controlling the operation of the circuit closing means according as the block signal system indicates an emergency or a caution condition of the track. 10 15

JOHN L. HAYTER.
